HYDROCARBON CONVERSION PROCESS

Frederick W. Sullivan, Jr., Hammond, Ind., assignor to Standard Oil Company, Chicago, Ill., a corporation of Indiana

Application December 30, 1933, Serial No. 704,773

6 Claims. (Cl. 196—9)

My invention relates to an improvement in the art of hydrocarbon conversion processes or in other words, to an improved process for the conversion of hydrocarbon gas and relatively heavy hydrocarbon oils to relatively light oils of the gasoline boiling range.

The commercial development of present day oil cracking processes has been long and complex but has been characterized by relatively few radical changes in the types of processes. First were the simple bulk distillation processes wherein relatively clean virgin charging stock was introduced into a direct-fired shell still and distilled under pressure until the residue in the still became too heavy for further heating without danger of coking. The next development was the Burton-Clark type of batch or semi-continuous process wherein the contents of the still were circulated through a tube heater instead of applying direct heat to the shell still. Then came processes of the tube or tube and drum type with "clean circulation" wherein the return of any heavy asphaltic cracked material to the heating section of the system was prevented.

All of these processes, however, use the principle of recycling, i. e., of recirculation of all or a substantial proportion of the insufficiently cracked material to the heating and reaction system. Once-through processes have been proposed, and used to a certain extent commercially, but were never successful on a commercial scale on account of the relatively low yield of gasoline which was possible by such processes.

I have discovered that by the use of elevated temperatures and pressures, i. e., higher temperatures and pressures than those normally used in commercial cracking processes, and by the use of a selected charging stock I may eliminate substantially all recycling and nevertheless obtain a high yield of gasoline. My particular discovery is that such a process can be operated economically on a commercial scale by separating the unconverted or insufficiently cracked material from the once-through reaction products and cracking the majority of said unconverted material to gases of an olefinic character, which gases are then recycled to the initial cracking step where polymerization and condensation to gasoline occurs. The operation of my process is as follows:

I utilize a selected charging stock, preferably gas oil of approximately 35° A. P. I. gravity which contains substantially no previously cracked material. In the initial cracking step the fresh charge is subjected to temperatures of 950—

1200° F. while under pressure of 750 to 3000 lbs. per sq. in. Cracked products, which may or may not be passed through a soaking drum, go to an evaporator or separator maintained at relatively low pressure where tar and asphaltic materials are eliminated. The overhead products from the evaporator are passed to a conventional bubble tower which may operate at the same or lower pressure as the evaporator and from which gasoline is eliminated as an overhead product. Heavy 10 gas oil is eliminated from the bottom of the bubble tower but this is not cycled in the conventional manner to the cracking step, although a part thereof may be returned to the process (subsequent to the heating system) as quenching oil. 15 Light gas oil may be likewise eliminated from an intermediate point in the bubble tower and a part of this may be recycled to the cracking step while another part, or substantially all thereof, may be utilized as quenching oil. 20

The degraded gas oil, or the balance thereof, which may have a density of 25-30° A. P. I., is then passed to a high temperature low pressure cracking step wherein it is cracked substantially completely to gases and heavy tarry or carbonaceous materials. This step may be carried out in a pipe heater or in any other suitable type of high temperature cracker. Following suitable separation steps, the olefinic gas from the high temperature low pressure cracking step is recycled to the inlet of the initial high pressure cracking step. Selected portions of the gas from the main cracking system may be joined with the gas oil therefrom prior to the high temperature low pressure cracking step. The 35 high temperature cracking step is preferably operated at temperatures of 1000°-1700° F. while under pressure of 0-200 lbs. per sq. in. above atmospheric.

The olefinic gases of the high temperature 40 cracking step undergo polymerization and interaction with fresh oil charged to the initial cracking step whereby greatly increased yields of gasoline are obtained, as compared with the ordinary once-through operation.

The foregoing represents a brief summary of my improved process, the full and complete description of which is as follows:

In the drawing attached hereto and forming a part of this specification, Fig. 1 is a diagrammatic elevational view of suitable apparatus for carrying out my process in one embodiment thereof, and Fig. 2 is a similar view of apparatus for carrying out my process in an alternative embodiment thereof.

The fresh oil charging stock is introduced into the system through line 10 by pumping means not shown. As charging stock I use a gas oil of approximately 30° to 40° A. P. I. gravity but may 5 use somewhat lighter or heavier stock, depending in part on the characteristics of the crude oil from which the stock is derived. I preferably use virgin or uncracked gas oil, i. e., a distilled fraction from crude oil containing substantially no 10 heavy asphaltic constituents.

The charging stock after preheating by suitable heat interchange means not shown is introduced into the coils of heater 11 wherein it is heated to temperatures of 950°-1200° F. while under pressures of 750-3000 lbs. per sq. in. The time of contact in heater 11 is ordinarily short, although heater 11 may be provided with a soaking section. I may also make use of an unheated soaking drum 12 following heater 11. If no soaking drum is 15 used, the heated products from heater 11 pass directly through line 13 and valve 14 to evaporator 15, the pressure being reduced at valve 14 to the desired evaporator pressure, which in general will be from 50 to 250 lbs. per sq. in. I may 20 also introduce relatively cool quenching oil from a suitable source (as later described) through line 16 and through valve 17, thus introducing the quenching oil just ahead of reducing valve 14, or may introduce the quenching oil through valve 25 30 18 located just following valve 14.

If soaking drum 12 is used, valve 14 is closed and valves 18a and 18b are opened in which case valve 18b functions as the pressure reducing valve for bringing the pressure down to the desired evaporator pressure. In this case I may 35 introduce quenching oil from line 19 through valve 20 located just ahead of valve 18b or through valve 21 located just subsequent to valve 18b. I may also introduce all or a part of the desired 40 quenching oil through line 16 and valve 22, which is located ahead of the soaking drum 12 whereby somewhat lower temperatures of 900°-1050° F. are maintained in the soaking drum 12. If the soaking drum is used the hot cracked materials 45 therefrom pass through line 23 to evaporator 15.

In evaporator 15 a pressure of 50-250 lbs. per sq. in. is maintained and the temperature is regulated by suitable cooling means to separate substantially all heavy tarry materials which are 50 removed by drawoff 24. These tarry materials may be eliminated from the system, or a part thereof may be pumped by pump 25 through cooler 26 and passed into line 19 or line 16 to serve as quenching oil as previously described, or part 55 thereof may be passed through valve 27 in line 28 thus being returned to evaporator 15 to act as a cooling medium therein. Evaporator 15 may also be cooled by heat interchange coils with fresh charging stock or by other suitable means. 60 Following evaporator 15 uncondensed vapors pass through line 29 to bubble tower 30. The pressure in bubble tower 30 may be the same as in evaporator 15 or may be regulated at some lower pressure by means of valve 31 in line 29. The operation of bubble tower 30 is conventional. Vapors of desired light products are removed through offtake 32 and unconverted gas oil is drawn off at the bottom of the tower through line 33. Suitable cooling means are provided which may include coils for heat interchange with fresh charging stock. The gas oil is withdrawn through line 33, and is withdrawn from the primary cracking system and utilized as later described, but a part thereof may be pumped by pump 34 through 70 cooler 35 and passed through line 36 to lines 16 75 cooler 35 and passed through line 36 to lines 16

or 19 to serve as quenching oil as previously described, or part may be passed through valve 37 and 37a in line 38 into evaporator 15 to serve as cooling medium therein, or may be returned through valve 39 in line 40 to serve as reflux and 5 cooling medium in bubble tower 30.

Bubble tower 30 may also be provided with trap-out tray 41 from which light gas oil may be withdrawn through line 42. This light gas oil may be further treated as later described, but 10 part thereof may be pumped by pump 43 through valve 44 and cooler 44b and returned to tower 30 as reflux or part may be passed through valves 45 and 45a in line 46 to pump 47 and admixed with fresh charging stock from line 10 prior to 15 entering heater 11. A part of the oil from line 46 may also be passed through valve 48 and cooler 49 to lines 16 or 19 to serve as quenching oil as previously described.

The vapors from bubble tower 30 are condensed in condenser 50 and passed through pressure regulating valve 51 into gas separator 52 which is ordinarily operated at essentially the same pressure as bubble tower 30 so that a relatively "dry" release gas may be separated through 25 line 53 and eliminated from the system, or utilized, as later described. Condensed light products are removed from separator 52 through line 54 and may be withdrawn from the system through valve 55. I may, however, provide my 30 system with a gasoline stabilizing tower in which case the condensed light products from line 54 pass through line 56 to stabilizer 57 which is provided with suitable reboiling means and reflux means whereby stabilized gasoline free from 35 undesirable light constituents is withdrawn through bottom offtake 58 while a relatively rich stabilizer gas is eliminated overhead to line 59 and is withdrawn from the system by valve 60, or otherwise utilized as later described. 40

The unconverted gas oil withdrawn from bubble tower 30 through line 33 is passed through line 61 and pump 62 through low pressure high temperature heater 63. I may also pass any part of light gas oil withdrawn from tower 30 by line 45 42 through valve 63a and thus to heater 63. Heater 63 is operated at temperatures of 1000-1700° F. and pressures of 0-200 lbs. per sq. in. above atmospheric whereby the gas oil is cracked substantially completely into gases of high olefin content plus heavy tar and carbonaceous materials. Heater 63 may be of ordinary pipe heater construction as illustrated, or may be of any other suitable construction, i. e., such as a refractory checkerwork which is alternately heated 55 by direct combustion, etc. I may also withdraw a part of the release gas from separator 52 and line 53 through valve 64 in line 65 and introduce same by pump 66 into heater 63 in admixture with gas oil charged thereto. I may also pass 60 all or a part of the stabilizer gas from stabilizer 57 and line 59 through valve 67 in line 68 to line 65 and pump 66 for admixture with oil charged to heater 63. If gas is admixed with oil charged to heater 63 I preferably preheat the gas by 65 heating or heat interchange means not shown, prior to admixture with the oil whereby vaporization is promoted. This admixture of gas with the oil charged to heater 63 not only facilitates operation of the heater by providing more complete vaporization of the charge, but also serves as an additional source of material from which gaseous olefins may be obtained.

Products from heater 63 are passed through line 69 to a suitable separator 70 which is pro- 75

vided with suitable cooling means, not shown, and from which tar and carbonaceous materials are removed through drawoff 71 while gases and vapors pass through line 72 to cooler 73 and thence through valve 74 to separator 75 wherein condensed light oils (which are formed to a small extent in heater 63) are withdrawn through valve 76 while high olefin content gases are removed through line 77 and valve 78 for use as later described.

I may also operate separator 75 at a somewhat elevated pressure in which case valve 74 is closed and valves 79 and 80 are opened whereby the materials from cooler 73 may be compressed to a suitably elevated pressure of 50-1000 lbs. per sq. in. by pump 81. Under these conditions the gas separated in separator 75 will consist primarily of methane and hydrogen which may be eliminated from the system through valve 82. If the light oils present in separator 75 are not sufficient in volume to effect this scrubbing and separation of methane and hydrogen from other desired gases, I may add additional scrubbing oil (through means not shown) to separator 75 whereby this purpose is effected. If separator 75 is operated at high pressure I remove the separated liquids through valve 83 in line 84 to stabilizer 85 which is operated at lower pressure or higher temperature to the end that light oils free from desired gases are removed through off-take 86 while desired olefinic gases are removed through off-take 87.

The gases produced in heater 63 and recovered from separator 75 and/or stabilizer 85 will ordinarily have a content of gaseous olefins in excess of 35% by volume, and if separator 75 is so operated as to eliminate substantial quantities of methane and hydrogen through vent 82 the olefin content of the total gases may be considerably higher, approaching as much as 70% by volume. These olefinic gases are passed through line 88 and compressor 89 and are admixed with charging stock to the process in line 10 prior to heater 11. Under the conditions prevailing in heater 11 these olefinic gases are substantially completely converted to desired products of the gasoline boiling range partly by direct polymerization and partly by complex interaction with the gas oil undergoing cracking in heater 11. I may also pass a part of the stabilizer gas from stabilizer 57 through line 59, valve 67, line 68 and valve 90 to join other gases in line 88 for treatment in heater 11.

Heater 11 is operated in the temperature and pressure ranges previously set forth, the rate at which oil is charged and the rate of heat input being such that at least 35% of the gas oil introduced is converted to lighter products of the gasoline boiling range. I prefer, however, to operate under such conditions that at least 45% of the gas oil is so converted. Due to the further conversion of the olefinic gases produced as previously described and to their interaction with the oil charging stock, the final yields of gasoline by my process will be from 65% to 80%, the gasoline being of high quality, in particular with respect to its antiknock quality. In addition, I achieve considerable economies in operating cost since the excessive amount of recycling per unit of fresh feed charged (which is customarily employed in present commercial processes) is eliminated thus reducing the necessary size of my equipment and eliminating excessive pumping costs.

In certain cases, depending largely on the quality and cracking characteristics of the avail-

able fresh charging stock, I may operate my process in two once-through high pressure-high temperature stages before eliminating unconverted material and cracking same to olefinic gases for recycling. Ordinarily I use this type of "dual once-through" process if the charging stock gravity is in the upper part of the range which I have previously disclosed as most suited for my process or, in other words, if the charging stock has a gravity of approximately 35° A. P. I. to 40° A. P. I., although slightly lower or higher gravities may be permitted in some cases depending on the distillation range of the charging stock and on its chemical characteristics, which latter are in general determined by the crude oil from which it is obtained. In this "dual once-through" modification of my process the apparatus used is essentially identical with that shown in the attached figure except that the gas oil eliminated from bubble tower 30 through lines 33 and 42 (except that part thereof which may be used as quenching oil or recirculated for reflux and cooling purposes) is passed to a second high pressure-high temperature heater identical with heater 11, the products from this second heater being passed into a separating system identical in function with separator 16, bubble tower 30, etc. (with or without intermediate passage through a soaking drum similar to drum 12). In this case the gas oil eliminated from the second bubble tower (except that portion thereof which may be used as quenching oil or for reflux or cooling purposes) is passed as previously described to the low pressure-high temperature heater 63. In this case the olefinic gases in line 88 may be pumped by pump 89 to either of the two high temperature-high pressure heaters, or may be divided in suitable proportion between both of said heaters, in order to obtain the best balance of operating conditions and results. In this modification of my process the overhead system following bubble tower 30 and the analogous bubble tower of the second stage is ordinarily combined, i. e. vapors from both bubble towers pass through a common condensing, separating and stabilizing system and the gasoline and gas from both stages are thereby collected as single streams. In fact I may make use of one bubble tower suitably divided at its midpoint, the cracked products from each stage being introduced respectively above and below the middle dividing point, the tower being so arranged that gasoline vapors and gas from both sections are collected in a common stream while the gas oil or unconverted material is collected in a separate stream from each section, these separate streams being processed as previously described.

For example, in the practice of this "dual once-through" modification of my process I may use apparatus as diagrammatically illustrated in Fig. 2 wherein all elements numbered from 11 to 90 are identical with corresponding elements similarly numbered of Fig. 1.

Referring to Fig. 2, the operation of the "dual once-through" modification of my process is as follows: I close valve 91 in line 61 and open valve 92 in line 93 whereby the intermediate oil separated in bubble tower 30 passes through line 93 to the high pressure-high temperature heater 94 which operates within the same range of temperature and pressure conditions previously described for high pressure heater 11 and wherein the oil is subjected to relatively high conversion but ordinarily to a lower conversion than that carried out upon the fresh oil in high pressure

heater 11. Following heater 94 the conversion products pass through line 95 and valve 96 to evaporator tower 97 which is operated under the same temperature and pressure conditions previously described for evaporator 15, the pressure on the conversion products being appropriately reduced at valve 96. By closing valve 96 and opening valve 98 the conversion products may be passed through reaction chamber 89 which is similar in construction and operation to previously described reaction chamber 12, and in this case the pressure is reduced at valve 100 prior to the products entering evaporator tower 97. From evaporator 97 heavy residual products are withdrawn from the system through valved line 101 while vapors pass overhead through line 102 and valve 103 prior to entering bubble tower 104, which is operated similarly to bubble tower 30 previously described. Vapors from bubble tower 104 pass through line 105 and join vapors produced in the first cracking step at the vapor exit from previously described bubble tower 30. Intermediate oils from bubble tower 104 are withdrawn from the bottom through line 106 and are sent by pump 107 through line 108 and valve 109 to the entrance of low pressure heater 63 previously described wherein these oils are converted to olefinic gases. These olefinic gases so produced after separation, etc., as previously described, may pass through valve 110 in line 88 to heater 11 as previously described or may wholly or in part be diverted through valve 111 in line 112 whereby said olefinic gases are passed to the inlet of the second stage high pressure oil heater 94.

35 The foregoing being a full and complete description of my invention, I claim:

1. A hydrocarbon conversion process comprising subjecting relatively high-boiling hydrocarbon oil to cracking at elevated temperatures and pressures to convert a substantial portion thereof into hydrocarbons of the gasoline boiling range, separating the cracked products into tar and vapors, fractionating said vapors to recover a condensate oil heavier than gasoline and said hydrocarbons of the gasoline boiling range, subjecting said condensate oil in a separate zone to cracking at higher temperatures and relatively low pressures to convert said condensate oil primarily to normally gaseous hydrocarbons of relatively high olefinic content and heavy tarry-like material, and returning olefinic gases thus produced to the initial cracking step for conversion into normally liquid hydrocarbons in the presence of said oil.

2. A hydrocarbon conversion process comprising subjecting relatively high-boiling hydrocarbon oil to cracking at elevated temperatures and pressures to convert a substantial portion thereof into hydrocarbons of the gasoline boiling range, separating the cracked products into tar and vapors, fractionating said vapors to recover a condensate oil heavier than gasoline and said hydrocarbons of the gasoline boiling range, subjecting said condensate oil in a second cracking step at elevated temperatures and pressures to convert a substantial proportion thereof to hydrocarbons of the gasoline boiling range, separating the cracked products into tar and vapors, fractionating said vapors to recover a second condensate oil and said last-mentioned hydrocarbons of the gasoline boiling range, subjecting said second condensate oil in a separate zone to cracking at higher temperatures and relatively low pressures to convert said second condensate oil primarily to normally gaseous hydrocarbons of relatively high olefinic content and heavy tarry-like material, and returning olefinic gases thus produced to the initial cracking step for conversion into normally liquid hydrocarbons in the presence of said oil.

3. A process in accordance with claim 1 wherein normally gaseous hydrocarbons are separated from the hydrocarbons of the gasoline boiling range resulting from said first-mentioned cracking operation and at least a part of said normally gaseous hydrocarbons are admixed with said condensate oil undergoing conversion primarily to normally gaseous hydrocarbons of relatively high olefinic content and heavy tarry-like material.

4. A process in accordance with claim 1 wherein hydrogen and methane are separated from the hydrocarbons of relatively high olefinic content prior to the return thereof to the initial cracking step.

5. A process in accordance with claim 1 wherein the relatively high-boiling hydrocarbon oil is a distillate oil containing substantially no asphaltic constituents and substantially no previously cracked constituents and is converted into at least 35% of hydrocarbons of the gasoline boiling range in passing once through the conversion zone.

6. A process in accordance with claim 1 wherein said condensate oil is subjected to a cracking temperature of about 1000°-1700° F. while under a pressure of about 0-200 lbs. per square inch.

FREDERICK W. SULLIVAN, JR.
